UNITED STATES PATENT OFFICE.

CHRISTIAN W. G. SODEMANN, OF ST. LOUIS, MISSOURI.

DUST-COLLECTING SHIELD FOR HEATING-RADIATORS.

1,358,994.

Specification of Letters Patent. Patented Nov. 16, 1920.

Application filed September 17, 1918. Serial No. 254,448.

To all whom it may concern:

Be it known that I, CHRISTIAN W. G. SODEMANN, a citizen of the United States, residing at St. Louis and State of Missouri, have invented certain new and useful Improvements in Dust-Collecting Shields for Heating-Radiators, of which the following is a specification, reference being had therein to the accompanying drawing.

10 My invention relates to a dust collecting shield for heating radiators, and has for its object to provide a deflecting shield to be adapted to steam radiators or hot water radiators, provided with means for collecting the dust which ascends in the current of heated air generated by contact of the atmosphere in the apartment with the heat radiator; and is an improvement upon United States Letters Patent No. 1,187,668, issued

15 June 20, 1916.

In the drawings—

Figure 1 is a vertical transverse sectional view of a structure embodying my invention;

20 Fig. 2 is a fragmental view in longitudinal section of the same;

Fig. 3 is a perspective view of a fragment of the top of the deflector;

Fig. 4 is a perspective view of the inner face of the top portion of one of the brackets employed in said structure;

Fig. 5 is an end view of the part shown in Fig. 3;

Fig. 6 is a top plan view of the part shown

25 in Figs. 3 and 5;

Fig. 7 is a perspective view of a shield embodying my invention.

As illustrated, I provide two brackets 10 whose general contour is shown in Fig. 1, the 30 vertical flange 11 extending along the rear edge and the horizontal flange 12 extending along the top edge. A series of lugs 13 project inwardly and in such location with reference to the flange 11 as to afford a seat for the outer vertical edge of the skirt or deflector 14, which is preferably of sheet steel, and is secured throughout its height to the flange 11 by means of bolts 15.

Between the flanges 11 and 12 is a curved 35 corner flange 16, and the skirt 14 is conformed to the inner face of said flange 16 as shown in Fig. 1, forming the roll 17. At the forward edge of the roll 17 the skirt 14 is cut to form the serration 18, at which point the 40 skirt 14 is bent upwardly to form the shoul-

der 19, and the skirt 14 thece is flattened forwardly to form a flat horizontal portion or superstructure-support 20 resting on the top of the flange 12 and secured thereto by bolts 21 (see Fig. 1). At its forward edge 45 the support 20 is cut away as indicated by the number 22 to permit the shoulder 23 to be formed. At the lower edge of the shoulder 23 the sheet is folded upon itself to form the flat edging 25, a single thickness of the 50 material projecting at each end of said edging 25 to form ears 26, which ears 26 are secured to the lower face of the flange 12.

The reversible superstructure 29 is added to the structure when desired, and contacts 55 closely with the top plane surface of the portion 20,—thus preventing the accumulation of dust between the top of the portion 20 and the lower face of the slab 29.

The flat superstructure 29 consists of a reversible frame 27 formed as shown in section in Fig. 2, the inwardly projecting flange 28 serving to support the metallic sheet 40. When the frame 20 is used in the position shown in Fig. 1 the flange 28 is surmounted 60 by the sheet 40, the fabric 41 is laid thereon (said fabric being decorative if desired) and a non-metallic slab 42 (preferably transparent to permit fabric 41 to be seen) surmounts the fabric 41,—all as in Fig. 1.

When a plain metal top effect is desired the frame 27 is reversed as in Fig. 2, the metallic sheet 40 being then flush with the top of the frame 27, and seated in place upon the flange 28.

65 The sheet 40 is apertured as indicated by 43 to be bolted (by bolts 21) or otherwise secured through openings in the top surface 20 of the skirt 14, and registering openings in the flange 12.

70 By means of the construction described I am enabled to provide a shield of indefinite length which is held straight and given a sufficient degree of rigidity by the shoulder formation of its top, so that it needs no stiffening attachment to the steam-radiator or hot-water-radiator upon which it is mounted, an inwardly-projecting foot 30 cast on the bracket 10 and resting on the top of the end loop of such radiator being a sufficient supporting means. I am enabled also to use a slab 42 of glass, marble or like frangible material having little tensile strength and therefore being liable to breakage when in use, the described means providing a flat and 75

105

110

adequate support for such slab 42, of whatever material said slab 42 is composed, throughout its length.

Toward its forward edge the flange 12 of the bracket 10 is cut away as indicated by 30^a; permitting a dust-collecting trough 21 to contact directly with the lower face of the metallic sheet 40 (see Fig. 1). The trough 31 is shallow and approximately 10 flat, as shown in section in Fig. 1, its ends are formed by elongated plates 32 having a rear extension 33, above which extension 33 a leaf-spring 34 constantly exerts its pressure to keep the trough 31 in closed position, so that it cannot be left open through inadvertance, having to be held in opened position by the hand of the operator during the operation of removing accumulated dust from its interior. The trough 31 is 20 provided throughout its length or at its ends with a pintle 35 whose projecting ends are journaled into the opening 36 in the brackets 10.

By the details of construction above indicated great economy of material and rigidity of the structure are attained, with a minimum of labor cost. At its lower edge the skirt 14 is folded upon itself to form the edging 37 if desired; but the stiffness and 30 strength of its upper portion are the more essential details incident to its construction.

As shown in Fig. 2 the metallic sheet 40 is dimensioned to exactly fit the frame 27 with its top plane level with the top of the 35 frame 27. When reversed, as in Fig. 1, the deeper side of the frame 27 is uppermost, so that enough space is left above the sheet 40, when in place above the flange 28, to accommodate the fabric-sheet 41 and 40 slab 42 and hold them securely in place; the slab 42, fabric-sheet 41 and sheet 40 being of the same superficial dimensions.

The primary object with which the superstructure 29 is made reversible, is to provide 45 the dealer with a shield both for commercial and non-commercial installations. With the use indicated in Fig. 1 the fabric-sheet 41 may be made of the same material and design of the wall-decorations of the room 50 in which the shield is placed, giving the architect a wide range of choice in decoration. For office, warehouse or other business installations the frame 27 is reversed as in Fig. 2, the fabric 41 and glass-top 42 are 55 omitted, and the metallic sheet 40 alone is

used to complete the superstructure 29. By this adaptability the shield of my invention may be stocked by the dealer in such manner as to provide a single line of shields adapted for church, residential or other use 60 in which decorative effect is desired, as well as for plain non-decorative business service, thereby reducing his investment and storage space requirements.

Having thus described my invention, what 65 I claim as new and desire to have secured to me by the grant of Letters Patent, is—

1. In a radiator shield, two end brackets having vertical and horizontal flanges; a metallic skirt mounted between said brackets upon the inner faces of the vertical flanges and the upper faces of the horizontal flanges; said skirt being provided with reinforcing edging at its horizontal edges formed by folding the skirt material upon 70 itself; and having stiffening shoulders extending from end to end at its top and a flat superstructure support formed between said shoulders.

2. The dust collecting shield for radiators 80 comprising two end brackets having inwardly-projecting vertical and horizontal flanges; a metallic skirt mounted within the vertical flanges and on top of the horizontal flanges; a superstructure seated on the top of 85 the horizontal portion of said skirt; and a dust-collecting trough pivotally mounted between said brackets and having its outer edge held normally and yieldingly in contact with the lower face of said superstructure. 90

3. The dust collecting shield for radiators comprising two end brackets having inwardly-projecting vertical and horizontal flanges; a metallic skirt mounted within the 95 vertical flanges and on top of the horizontal flanges; a superstructure seated on the top of the horizontal portion of said skirt; and a dust-collecting trough pivotally mounted between said brackets and having its 100 outer edge held normally and yieldingly in contact with the lower face of said superstructure; said superstructure comprising a reversible frame, a metallic sheet, and a non-metallic sheet arranged to be held by 105 said frame.

In testimony whereof I hereunto affix my signature.

CHRISTIAN W. GEODEMANN.
